Charles W. Kenner,

BY
Frank H. Allen,

ATTORNEY,

UNITED STATES PATENT OFFICE.

CHARLES H. KENNEY, OF NEW LONDON, CONNECTICUT.

STEAM-GENERATOR.

SPECIFICATION forming part of Letters Patent No. 611,412, dated September 27, 1898.

Application filed December 31, 1897. Serial No. 665,232. (No model.)

To all whom it may concern:

Be it known that I, CHARLES H. KENNEY, a citizen of the United States, residing in the city and county of New London and State of Connecticut, have invented certain new and useful Improvements in Steam-Generators, which improvements are fully set forth and described in the following specification, reference being had to the accompanying two sheets of drawings.

My invention is in steam-generators of the class in which combined pipes and drums are employed, this class of generators being used to a considerable extent in vessels and like places where space must be economized but where a generator of great steaming capacity must be provided.

My object in producing this invention is to provide a generator any or all of whose component parts may be removed and replaced by removing the front of the casing or shell inclosing said parts, and I also have in view the production of a generator in which steam may be gotten up quickly and in which the caloric products of combustion may be utilized to the greatest extent possible.

In order to clearly explain my invention, I have provided the annexed drawings, in which—

30 Figure 1 is a front elevation of a steam-generator of my newly-improved form with a portion of its front broken away to expose the interior part, and Fig. 2 is a central vertical sectional view taken on line xx of said Fig. 1. 35 Figs. 3, 4, and 5 are detail views illustrating the form and arrangement of certain pipes hereinafter referred to more particularly. Fig. 6 is a plan view of portions of the sheet-metal casing of the generator proper; and 40 Fig. 7 is an enlarged view of a portion of the downflow-pipe 13^a and of one of the circulation-pipes 17, explaining the means utilized to connect the said pipes.

The case or shell of my generator is of boiler-iron and is here shown as of rectangular form. Located in the upper central part of said case and extending nearly from front to rear of the same is a steam-drum, that is indicated by the reference-figure 10, and immediately below and parallel with said steam-drum is a water-drum 11, these two drums be-

ing connected near their front and rear ends by pipes 12, through which water in the upper drum, resulting from condensation or other causes, may drip into the water-drum 11. 55

Reference-figures 13 14 denote pipes leading from the front end of the water-drum in opposite directions to the sides of the generator, where they pass downward to a level sufficiently low to bring them within the 60 combustion-chamber, where they are again deflected and extend along the sides, as at 13^a 14^a, and finally along the rear, as at 13^b 14^b, where they meet at the center. At this central rear point they are connected with a 65 similar pipe 15, that leads downward from the rear end of the water-drum 11. (See Fig. 3, which is a rear end view of the steam and water drums and of certain of the pipes connected with said drums.) It will thus be 70 seen that provision is made for the free downflow of the water from the drum 11 through pipes 13 and 15 into the pipes 13^a 14^a 13^b 14^b and that these last-named pipes are located within the fire-pot or combustion- 75 chamber, where their contents may be best influenced by the intense heat of the fire.

The feed (water) pipe of my boiler is indicated by the figures 16 and is located in the upper part of the casing, preferably at or 80 about the level of the top of the steam-drum. This pipe 16 branches to the right and left hand just inside the casing, as at 16^a 16^b, and thence passes in the form of three superimposed sets of coils 16^c, 16^d, and 16^e back and 85 forth from front to rear of the generator at each side of the steam-drum 10, as is clearly shown in the drawings. The lower coil 16^e is connected with and leads into vertically-arranged loops 16^f, extending from front to 90 rear at the sides of the generator, and the terminals of said pipes 16^f are connected (at the rear end of the generator) with pipes 16^g, that meet in a pipe 16^h, which discharges into the water-drum 11. By means of this arrangement of feed-pipes the water is subjected 95 for a considerable length of time to the hot air within the casing of the generator and becomes heated almost to the point of steaming before it passes into the drum 11. 100

The water-drum 11 is connected on each side by means of a large number of circulation-

pipes with the pipes 13^a 14^a, which I have already described as located at each side and within the combustion-chamber. These pipes 17 are tapped into said pipes 13^a 14^a and extend upward to a point somewhat above the fire-pot and thence extend inward to the center of the generator and back again to the side in a series of superimposed vertical coils 17^a, the inner end of the upper of said coils 10 being carried upward and tapped into the steam-drum 10, as best seen in Figs. 1 and 2. The space between the pipes 17 (at opposite sides of the generator) and below the lower coils 17^a is utilized as the fire-pot, the grate 15 (not shown) being located at or near the level of line z of Fig. 1. The ash-pit is indicated by reference-figures 18.

Referring now to Figs. 2, 3, and 4, it will be seen that the pipes 13^b and 14^b at the lower 20 rear part of the fire-pot have tapped into them a number of pipes 19, that extend upward to about the level of the water-drum 11 and then extend forward nearly to the front of the generator, as at 19^a, thence back again, and 25 finally upward nearly to a level with the center of the steam-drum, where they are screwed into a horizontal pipe 20, whose central portion is connected with said steam-drum by a short pipe 21, and whose ends are connected 30 by means of vertical pipes 20^a 20^b with the elbows that connect the lower pipes 13^a with 13^b and 14^a and 14^b. (See Figs. 2 and 3.) The water-level should be maintained at about the height indicated in Fig. 1—that is to say, at 35 or near the level of the top of the water-drum 11.

The pipes 17 should be located as close together as possible, and I have found it convenient and practicable to connect said pipes 40 with the pipes 13^a 14^a by means of nipples 22, that are tapped with a right-hand thread to receive pipes 17 and are formed at their other end with an extension that is provided with a left-hand thread adapted to be screwed into 45 said pipes 13^a 14^a. With this form of connection it is necessary to leave only space enough between pipes 17 to work a "spanner-wrench." The same form of connection may be utilized to connect the pipes 19 at the rear 50 of the generator with pipes 13^b 14^b and also with the upper pipes 20.

The casing of my generator, as I have stated, is made of sheet metal, and I have secured the front in position in such manner that it 55 may be removed entire or in sections in order that the interior of the casing may be reached whenever it becomes necessary to inspect or repair the interior parts of the generator. I have illustrated said front as formed of four 60 sections, although the number is not material so long as they are each of a size convenient to be handled. These sections are provided at their meeting edges with angle-irons 23, that are securely joined by means of bolts 24; 65 and it will now be understood that either or all of the front sections may be detached by simply removing the bolts 23. For ordinary

repairs, however, or for cleaning out between the pipes which I have described in detail doors 25 are provided near the upper part of 70 the generator and opposite the space just above the pipes 19^a. The feed-doors 26 may also be utilized when it is desired to clean out the fire-pot or repair the pipes surrounding or near the same.

The arrangement of all the pipes and other elementary parts of my described generator is such that they may each be readily reached, removed, and replaced without disturbing the other parts, this being very desirable in marine boilers, which, as a rule, are so located that it is either impossible or very inconvenient to remove them from the vessel's hold for repairs.

It will now be understood that in a boiler 85 of large size the space above the horizontal pipes 19^a will be such that a man may easily enter through the upper doors 25 or through the lower (feed) doors and thus reach every 90 one of the pipes or other interior parts in order to disconnect and remove the same without disturbing the shell or casing of the generator.

The reference-figure 26 indicates a steam-pipe leading outward from the steam-drum 95 10, and 27 denotes the smoke-stack.

28 indicates a "separator-plate" located horizontally at or near the center of the steam-drum 10 and in such relation to the pipes 17^a that any water that may be discharged 100 through said pipes into the drum will be checked and caused to fall to the bottom of said drum, whence it passes by gravity through the pipes 12 downward into the water-drum 11.

By removing the entire front of the casing, as already explained, the interior parts of the generator may be entirely removed and rebuilt without disturbing the rest of the casing.

At one or more points in the lower part of 110 the pipes 13^a 13^b I have provided "blow-off" cocks 29, by means of which the water may be drawn off or any sediment that may collect in said pipes may be blown off.

Having described my invention, I claim as 115 new and wish to secure by Letters Patent—

1. In combination in and with an inclosing case, a steam-drum, an independent water-drum located below said steam-drum, connections between said drums, downflow-pipes 120 leading from the water-drum to and around the lower sides and rear of the generator, and pipes connecting said downflow-pipes with the said steam-drum, substantially as described.

2. In combination in and with an inclosing case, superimposed independent steam and water drums and connections between said drums and a feed-water pipe arranged in superimposed coils or loops at the sides of said drums, substantially as set forth; said feed-water pipe being arranged to discharge into said water-drum.

3. In combination with a pipe-boiler of the

class referred to, an inclosing shell having a removable front composed of outwardly-flanged sections as set forth, and bolts connecting said flanges upon the outer face of said front, substantially as specified.

4. In combination in a boiler of the class referred to, superimposed independent steam and water drums and connections for the same as set forth, downflow-pipes extending downward from the water-drum and along the sides and rear of the generator, and pipes 17 connecting said downflow-pipes with the steam-drum, the pipes 17 being secured to the said

downflow-pipes by right and left hand nipples, substantially as specified.

5. In a steam-generator of the class referred to, in combination with a steam-drum, a separator-plate located near the longitudinal center of said drum, inlet-pipes 17^a discharging into said drum below said plate, and drip-pipes 12, all substantially as and for the purpose specified.

CHARLES H. KENNEY.
